UNITED STATES PATENT OFFICE.

ROSCOE STEELE, OF ROCKAWAY, NEW JERSEY, ASSIGNOR TO WIREBOUNDS PATENTS COMPANY, A CORPORATION OF MAINE.

MACHINE FOR USE IN MAKING BOXES.

Application filed August 1, 1922. Serial No. 578,989.

This invention relates to improvements in box blank machines and particularly to improvements in machines for making wire bound box blanks by attaching wires and cleats to sheet material and in which the box materials are fed intermittently past stapling mechanism which drives staples into the work during the intervals between feed steps. Such machines are usually provided with mechanism for controlling the relative progression between the work and the stapling mechanism in order to position the staples at predetermined, selected points in the work. A wire bound box blank machine of the class described is shown, for example, in the patent to Seraphine F. Bauwens, 1,437,386 granted November 28, 1922.

Among other objects, the present invention is intended to provide such a machine with an improved braking mechanism whereby the feed of the box parts may be more accurately controlled to position fasteners at the predetermined, selected points in the work.

The invention will be best understood by reference to the accompanying drawings, in which

Fig. 1 is a side elevation of a wire bound box blank machine embodying the invention;

Fig. 2 is an end view of the machine viewed from the left in Fig. 1;

Fig. 3 is a sectional view taken on the line A—A of Fig. 2.

The illustrative machine comprises generally work-forwarding chains 1 to position and feed the box materials beneath staplers 2 which apply binding wire to the box materials by forming and driving staples over the binding wire into the box materials.

The staplers 2, which may be of the type shown in the reissue patent to Thompson No. 15,045 of February 15, 1921, are operated through a pitman 3 from an eccentric 4 on a main shaft 5 and are adapted at each operation to form a staple from staple wire fed thereto and drive the same over the binding wire into the box materials.

The work-forwarding chains 1, which are trained over driven sprocket wheels 6 on a shaft 7 at the delivery end of the machine and over idler sprocket wheels 8 on a shaft 9 at the receiving end of the machine, are advanced intermittently by a ratchet and pawl mechanism comprising a ratchet wheel

10 on shaft 7 and a pawl 11 carried by a lever 12 pivotally mounted on one end of shaft 7 and having a pin and slot connection at the other end with a link 13 extending from an eccentric 14 on main shaft 5, the pin and slot connection above referred to providing for lost motion between the ratchet and pawl mechanism and the eccentric 14 to permit controlling the extent of the drive stroke of the feed pawl 11 to position fasteners at selected points in the work.

The mechanism for controlling the feed steps of the work to position the fasteners at selected points in the work is illustrated and described in the patent to Seraphine F. Bauwens above referred to and need not be described in detail herein. It consists generally of mechanism to control the return or inoperative stroke of the feed pawl 11 thus controlling its operative or drive stroke. The specific mechanism shown in the drawings comprises a lever 15 rigidly connected to the pawl carrying lever 12, a rod 16 connecting lever 15 with a stop mechanism (not shown) of the pawl and rack type (shown in said patent to Seraphine F. Bauwens), said stop mechanism being controlled by spacer blocks or other members carried by the work-forwarding chains 1 to control the feed steps of the work to position the fasteners at selected points in the work.

To accurately position the fasteners at the selected points in the work it is desirable to stop the movement of the conveyer chains immediately upon the termination of each drive stroke of the feed pawl 11 and hold the chains stationary during the fastener-driving operation. Various braking mechanisms have been heretofore used in machines of this class which are momentarily thrown into operation at the termination of each drive stroke of the feed pawl but it has been found in practice that after such a brake is released the conveyer chains have a tendency to shift due to the back pull of the binding wire or other causes, thus rendering the accurate positioning of fasteners in the work difficult.

Applicant's invention contemplates a braking mechanism which is automatically thrown into operation at the termination of each drive stroke of the feed pawl and which will hold the conveyer chains against movement until the feed pawl starts its next drive stroke.

As shown in the drawings, the brake is placed on the shaft 7 and is operated by a cam block 32 keyed to the main shaft 5 which cam block is so proportioned that the 5 brake is thrown on at the termination of the drive stroke of the feed pawl 11 and held in braking position until the fastener-driving operation of the staplers is completed. The 10 braking mechanism comprises a brake wheel 17 keyed to shaft 7 and a divided brake shell 18 having a brake lining 19, the sections of which are pivotally connected at 20. The 15 brake shell and its lining are supported by a bracket 21 the upper end of which is bolted to a cross-frame member 22 and the lower end of which is loosely mounted on the shaft 7 (see Fig. 3). One end of the divided brake shell is secured to the bracket 21 and the other end is connected by a pin 23 to the upper end of a fulcrumed lever 24 pivoted to the bracket 21 at 25 so that when the lower end of lever 24 is moved to the left, as shown in Fig. 3, the brake shell will be expanded 20 and lock the shaft 7 which carries the sprocket wheels 6 against further rotation.

For moving the lever 24 to expand the 25 brake shell at the termination of a drive stroke of the feed pawl and for holding the brake shell in an expanded position during a 30 stapling operation, the lower end of lever 24 is connected by a pin and slot connection to a threaded sleeve 26 which encases and holds a screw rod 27 which is pivotally connected to a lever 28 at 29. The upper end of lever 35 28 is pivotally secured to the bracket 21 at 30 and the lower end carries a roller 31 which is held by means of a spring 33 against the cam block 32 keyed to the main shaft 5. The spring 33 also serves to release 40 the brake when the cam block 32 permits movement of the lever 28 to the right viewing Fig. 3.

It will be noted that the cam block 32 is so proportioned that the brake will be on during 45 approximately one-half a revolution of the main shaft 5 and will be off during the other half revolution of said shaft, thus locking the conveyer chains against movement during the intervals between feed 50 steps of the work and while the staples are being driven. The brake may be adjusted by turning the screw rod 27.

Among other advantages, applicant's 55 brake mechanism is simple in construction, has few parts, is easily adjusted and, being controlled as it is by a cam block on the main shaft, will positively lock and hold the conveyer chains against movement during the periods between drive strokes of the 60 feed pawl and while the staples are being driven thus assisting materially in the positioning of fasteners in the work and producing a better box blank.

Obviously, the present invention is not 65 limited to the particular embodiment shown

and described but may be variously embodied and the particular construction shown may be variously modified as will appear to those skilled in the art. Furthermore, it is not indispensable that all the features of the 70 invention be used conjointly since they may be used to advantage in various different combinations and sub-combinations.

Having described one embodiment of my 75 invention, I claim:

1. A machine for use in making boxes comprising, in combination, a support for the box parts; fastener-setting mechanism; means to cause relative step-by-step progression between said mechanism and the box 80 parts; means to vary the extent of said step movements; and a cam operated brake to lock the box parts and fastener-setting mechanism against relative movement during each interval between said step-by-step 85 progression and while said interval occurs.

2. A machine for use in making boxes comprising, in combination, fastener-setting mechanism; means to feed the box parts intermittently past said mechanism; means to 90 vary the feed steps of the box parts and a cam operated brake to lock the box-part feeding means against movement during each interval between feed steps and while said interval occurs.

3. A machine for use in making wire-bound boxes comprising, in combination, a support for the box parts; binding-wire applying means including fastener-setting mechanism; means to cause relative step-by- 100 step progression between said mechanism and the box parts; and means to lock the box parts and fastener-setting mechanism against relative movement during the intervals between step movements comprising a 105 brake and means automatically to throw on the brake and hold it in braking position while an interval between step movements occurs.

4. A machine for use in making boxes 110 comprising, in combination fastener-setting mechanism; means to feed the box parts intermittently past said mechanism; means to vary the feed movements of the box parts; and means to lock the box-part feeding means 115 against movement during the intervals between feed steps comprising a brake and means automatically to throw on the brake and hold it in braking position while a fastener-setting operation is taking place.

5. A machine for use in making wirebound boxes comprising, in combination, binding-wire-applying means including fastener-setting mechanism; means to feed the box parts intermittently past said mechanism; and means to lock the box-part feeding means 125 against movement during the intervals between feed steps comprising a cam-operated brake adapted to lock the work-forwarding means at the termination of a feed step and 130

hold the same against movement while a fastener-driving operation is taking place.

6. In a machine of the class described, the combination of a shaft 7, sprocket wheels 6 keyed to said shaft, endless work-forwarding chains trained over said sprocket wheels, a ratchet and pawl mechanism to advance the work forwarding chains intermittently, another shaft 5, an eccentric 14 thereon for operating said ratchet and pawl mechanism, fastener-setting mechanism to drive fas-

teners into the work during the intervals between feed steps of the work, a brake carried by the shaft 7, and a cam block 32 on the shaft 5 to operate the brake and lock the work-forwarding chains against movement while an interval between step movements occurs. 15

In testimony whereof, I have signed my name to this specification.

ROSCOE STEELE.
